UNITED STATES PATENT OFFICE.

EDMUND P. KINNE, OF ALLIANCE, OHIO, ASSIGNOR TO AMERICAN STEEL FOUNDRIES, OF NEW YORK, N. Y., A CORPORATION OF NEW JERSEY.

PILOT-COUPING.

1,009,974.

Specification of Letters Patent. Patented Nov. 28, 1911.

Application filed January 29, 1910. Serial No. 540,732.

To all whom it may concern:

Be it known that I, EDMUND P. KINNE, a citizen of the United States, residing at Alliance, in the county of Stark and State 5 of Ohio, have invented certain new and useful Improvements in Pilot-Couplers, of which the following is a specification.

My invention relates to couplers of the Janney and other types employing a pivot 10 knuckle and a vertically movable lock, and more particularly relates to such couplers as applied to the pilots of locomotives or the end sills of tenders. In the use of couplers for this purpose it will be understood that 15 a short shank is employed, the shank being seated in a pocket secured to the end sill of the locomotive or tender. In such instances, the coupler necessarily has considerable over-hang or, in other words, extends for some 20 distance outside the plane of the end sill as distinguished from couplers applied to freight-cars where the coupler almost underlies the end sill. In the latter case, the lock-lifting mechanism may be applied to the end 25 sill of a car and the lock may be lifted in substantially a vertical line. However, in the present case, wherein the coupler has an exaggerated over-hang, any lock-lifting mechanism applied to the end sill of a car 30 will operate the lock at a decided disadvantage due to the angle at which the lifting force is applied. This has been overcome to a certain extent by the employment of a long lever arm attached to the transverse 35 operating rod, the lever arm extending to a point substantially over the coupler head. This long arm, however, is unwieldy, becomes bent and broken very easily and is generally unsatisfactory.

Therefore, one of the principal objects of my invention is to provide a lock operating mechanism by which the full power of the transverse operating shaft may be applied to lift the lock and throw the knuckle when 45 required.

A further object of my invention is to provide operating mechanism of this character so arranged as to move freely with the coupler when rounding curves or operating 50 on short angle sidings.

A further object of my invention is the provision of an operating mechanism which will permit the operating handle to assume its normal or lowered position, under the influence of gravity, when it is released, in-

dependently of the lifter, and irrespective of whether the lifter is in its raised or lowered position.

Another object of this invention is to provide a mechanism which can be readily assembled and which will be maintained in operative relation to the coupler, by a single bolt or pin, thereby simplifying the structure and obviating the necessity of numerous independent pieces such as bolts, turnbuckles, etc., which are ordinarily employed.

My invention will be more readily understood by reference to the accompanying drawings wherein—

Figure 1 is a plan view and Fig. 2 is a side 70 elevation of a pilot coupler having my novel operating mechanism applied thereto.

It will be understood that my invention is shown as applied to a coupler of the Janney type, having a vertically movable member which may either be a lock or a lifter for a lock. However, for the sake of clearness, this member will be designated as a lock.

Referring more particularly to the drawings it will be seen that to the end sill 3 of a tender or locomotive is secured a casting 4 having an opening therein which in vertical dimension is greater than the shank of the coupler and which in horizontal dimension 85 is flared toward its mouth in order to permit swinging or side-wise movement of the coupler and its short shank. The coupler head 6 having short shank 5, is mounted within the opening in the casting 4, being 90 held therein by means of the pivot pin 9. The coupler is provided with the usual knuckle 7 and lock and knuckle opener 8. Shims 10 are placed in the pocket pivot coupler. In the present instance, these 95 shims perform a useful function in that when the wheels of the locomotive or tender become worn or when the springs become weakened and depressed the coupler may be raised to matching position with couplers of 100 standard height by removing one or both of the shims 10 and placing them underneath the shank of the coupler instead of above.

The transverse shaft 11 is mounted in 105 suitable brackets 12 secured to the end sill 3, this shaft having operating handles 13, one at each end of the end sill. To the shaft 11 is secured a short lever arm 14 having a slot 15 therein. A link or connecting rod 110

16 has one end seated in the slot 15 and the other end in a slot 17 in a right-angled bell crank lever 18. This bell crank is provided at one end with bearing trunnions 19 which 5 are adapted for co-operation with a recess 20 in the casting 4. The other end of the bell crank lever is bifurcated and is connected to the lock 8 by means of a pin 21. It will be noted by reference to Fig. 1 that 10 the trunnions 19 have their ends rounded thus permitting lateral movement of the bell crank lever 18 to the extent of the slot above the bearing recess 20. In assembling this mechanism, the end of the connecting link 15 16 is inserted into the slot 15 in the lever 14 and the other end of the link is inserted through the slot 17 and the bell crank lever 18. The trunnions 19 are then slid into the open-ended bearings, and the other end of 20 the bell crank lever is connected to the lock 8 by the pin 21. It will be evident that the various parts are all held together by the single pin 21, and by simply removing this pin all of the structure may be taken apart, 25 and, furthermore, that the various loose pieces such as turn buckles, nuts, etc., ordinarily employed, are entirely eliminated.

It will be seen that by my device the lock of the coupler may be lifted with the least 30 possible loss in the force exerted on the handle 13. It will also be seen that this force is exerted at whatever angle the coupler is positioned. It will also be seen that if the lock is placed in lock-set position that 35 the operating handle may, by reason of the slots in the various parts, return to its normal unexposed position; also that if the shims 10 are shifted, thus raising the coupler, that the slots in the lock 8 and bell crank 18 40 will permit such elevation without disarranging the operating mechanism.

My invention is particularly applicable to couplers having a large amount of overhang and is not particularly adapted to 45 couplers as applied to freight cars.

While I have shown and described a preferred embodiment of my invention, it will be understood that various changes in the construction and minor mechanical details may be made without departing from the 50 spirit of the invention or sacrificing any of the material advantages thereof.

What I claim is:

1. In a device of the character described, 55 the combination of a coupler provided with a knuckle and a locking member, a body to which said coupler is attached, provided with a slotted bearing, a bell-crank lever having at one end a bearing member pivotally mounted in said bearing said lever having at its other end a slotted connection with said locking member and means for operating said bell-crank lever to lift the locking member, substantially as described.

2. In a device of the character described, 60 the combination of a coupler provided with a knuckle and a locking member, a body to which said coupler is attached, provided with a plurality of open-ended slotted bearings, a bell-crank lever pivotally mounted 65 in said bearings, connections between said bell-crank lever and the locking member, and means for actuating said bell-crank lever to operate the locking member, substantially as described.

3. In a device of the character described, 70 in combination, a coupler head, a knuckle and a lock therefor, a supporting member to which said coupler head is connected provided with slotted bearings, a lever having trunnions adapted to rest in said bearings, said trunnions being rounded at their ends to permit swinging movement of the lever, and connections between said lever and the said lock, substantially as described. 75 80
